UNITED STATES PATENT OFFICE.

CHARLES H. PATTEN, OF PROVIDENCE, RHODE ISLAND, ASSIGNOR TO REX MANUFACTURING COMPANY, OF PROVIDENCE, RHODE ISLAND, A CORPORATION OF RHODE ISLAND.

MECHANICALLY-OPERATED LEAD PENCIL.

Application filed February 12, 1927. Serial No. 167,740.

This invention relates to improvements in mechanically-operated lead pencils of the type having a magazine from which leads may be fed continuously one following another by a reciprocating movement of the feeding mechanism; and the object of this invention is to provide an improved clutch means for gripping and feeding the lead to working position.

10 A further object of the invention is to construct the clutch for gripping and feeding the lead forwardly by pivotally mounting a plurality of jaws with means for causing these jaws to grip the lead at one end 15 of its reciprocating stroke and release the lead at the opposite end of its reciprocating stroke.

With these and other objects in view, the invention consists of certain novel features 20 of construction, as will be more fully described, and particularly pointed out in the appended claims.

In the accompanying drawings:

Figure 1 is a sectional view of the pencil 25 with the jaws in retracted gripping position.

Figure 2 is a sectional view showing the feed mechanism moved to its forward position with the jaws released for return to retracted position.

30 Figure 3 is a central sectional view of the lead guide tube.

Figure 4 is a sectional end view of the guide tube on line 4-4 of Figure 3.

Figure 5 is a central sectional view of the 35 plug for one end of the lead magazine which also acts as an abutment for one end of the spring for moving the lead-guiding tube to retracted position.

Figure 6 is a central sectional view of the 40 abutment member for one end of the bore of the point end bushing.

Figure 7 is a central sectional view of the 45 cylindrical collar for operating the jaws by a sliding movement along the outer surface of the lead-guiding tube.

Figure 8 is a perspective view of one of the jaw members of the clutch.

Figure 9 is a sectional view on an enlarged 50 scale showing the relation of the clutch mechanism and its operating collar as mounted in a point end bushing.

Figure 10 is a section on line 10-10 of Figure 9.

It is found in practice desirable to provide a mechanically-operated pencil, the leads of 55 which may be fed forward one after the other from a magazine in which they are stored into working position by pressing the rear end of the pencil, it being especially desirable that the clutch mechanism for 60 feeding the leads may be positive in its action and in order to provide a practical and yet simple clutch means, I have provided a plurality of longitudinal slots in the lead guide tube with an annular recess in the 65 outer surface of the tube intermediate the ends of the slots and positioned jaws in the slots with laterally deflected fingers in the annular recess to provide a pivot point about 70 which the jaws may be rocked by sliding a collar along the surface of the tube; and the following is a detailed description of the present embodiment of this invention and showing one means by which these advantageous results may be accomplished:— 75

With reference to the drawings, 10 designates the barrel of a pencil, which may be of rubber, metal, celluloid or other suitable material with a point bushing 11 threaded into one end thereof to support a point sleeve 80 12 which is secured in position by means of a steel point end 13 having threaded engagement as at 14 with the bushing 11. The feed mechanism for the leads of the pencil is mounted in the point end bushing 11 and 85 comprises a lead-carrying tube 15 having longitudinally-disposed slots 16 therein and an annular recess 17 in its outer surface which is positioned intermediate the ends of the slots 16. Jaws 18 shaped as illustrated 90 in Figure 8, are positioned in the slots and each has a finger portion 19 deflected laterally therefrom to lie in the recess 17 about which the jaw member may rock as a pivot.

These jaws are so shaped as to provide an 95 enlarged portion 20 at one end which when the jaws are in released position, as illustrated in Figure 2, project beyond the surface of the tube 15 and the opposite end of the jaws 21 is so formed that when the jaws 100 are in gripping position as illustrated in Figure 1, this portion 21 extends beyond the

surface of the tube 15 in a like manner, and in order that these jaws may be moved to grip and release position, I have mounted a collar 22 which substantially fits 5 the lead-carrying tube 15 to slide therewith so that when the collar is in the position shown in Figure 1 it will cause the jaws to grip the lead while when the collar is in the position shown in Figure 2, it will engage 10 the ends 21 of the jaws 17 to move these jaws to released position, as illustrated in Figure 2. The tube 15 with its collar and clutch jaws is positioned in the bore 23 of the point end bushing 11, which bore is reduced as at 24 to form a shoulder 25 against which the collar 22 contacts to limit the movement in one direction, the bore 24 being of a size to permit the tube 15 and the clutch mechanism with jaws 17 in their most extended position to slide therein.

20 A stop shoulder 26 is formed at the opposite end of the bore 23 by means of an abutment member 27 in threaded engagement with the bushing 11. In order that the lead-carrying tube may move to its retracted position, I have provided a spring 28 which engages with the abutment member 27 and a shoulder 29 of a plug 30 secured to the lead-carrying tube to move this tube relative to the barrel 10 and bushing 11 to its retracted position. The plug 30 which is threaded into the end of the tube 15 and provided with a bore 31 which is flared as at 32 to direct the leads 33 of the magazine 34 into the bore 31 and thence to be gripped by the clutch jaws 17, as illustrated in Figure 1.

30 Manual pressure applied to the rear end 35 of the pencil causes a movement of this end relative to the barrel 10. An endways movement of this character is transmitted through the magazine tube 36 slidably mounted in the plug 37 to the lead-carrying tube 15 through the plug 30 to move it from 40 the position illustrated in Figure 1 to the position illustrated in Figure 2. By such movement the lead 38 is fed forwardly into the friction guide tube 39 where it is retained during the return movement of the 45 jaws 17 to their retracted position under influence of spring 28 to secure another grip on the lead for further movement when desired.

50 The magazine tube 36 is prevented from rotation in its guide plug 37 by means of a slot 40 in the tube with the finger 41 extending into the slot and is limited in its reciprocating movement by means of spun annular projections 42 and 43.

55 It will be apparent that the extent of feed of the lead from each reciprocating stroke may be varied by the length of the bore 23 or the collar 22 may be held stationary and the length of the reciprocating feed varied by the length and shape of the jaws 21

moved therethrough as will be readily apparent to a mechanic skilled in this art.

It will be seen that I have provided a construction of clutch for feeding the leads of the pencil, which is positive in its release 70 of the lead at each end of its reciprocating stroke and that this result is accomplished by simple and practical construction which is comparatively inexpensive to manufacture.

The foregoing description is directed 75 solely towards the construction illustrated, but I desire it to be understood that I reserve the privilege of resorting to all the mechanical changes to which the device is susceptible, the invention being defined and 80 limited only by the terms of the appended claims.

I claim:

1. A mechanical lead pencil including a barrel portion, a lead guide tube mounted 85 therein for reciprocating movement relative thereto, pivotally mounted jaws extending through the walls of said tube, and means for causing said jaws to grip and release a lead in said tube at opposite ends of a 90 reciprocating stroke of said tube relative to said barrel.

2. A mechanical lead pencil including a barrel portion, a lead guide tube mounted 95 therein for endways movement relative thereto, a plurality of jaws extending through the walls of said tube, means for pivotally mounting said jaws intermediate their ends, manually operable means for reciprocating said tube relative to said barrel, 100 and means for operating said jaws to grip the lead at one end of the reciprocating stroke and release said lead at the opposite end of said stroke.

3. A mechanically-operated pencil including 105 a barrel portion, a lead-guide tube mounted in said barrel for endways movement having spaced longitudinally-disposed slots in the wall of said tube and an annular recess in its outer surface, jaws in said 110 slots having laterally-deflected fingers in said recess about which they swing as a pivot, a collar slidably along said tube to operate said jaws, means to reciprocate said tube relative to said barrel, and means for 115 causing said collar to move relative to said jaws upon the reciprocation of said tube.

4. A mechanically-operated pencil including 120 a barrel portion, a lead guide tube mounted in said barrel for endways movement having spaced longitudinally-disposed slots in the wall of said tube and an annular recess in its outer surface between the ends of said slots, jaws in said slots having 125 laterally-deflected fingers intermediate their ends in said recess about which they swing as a pivot, a collar slidably along said tube to operate said jaws, said jaws being so shaped as to have portions at one end extend beyond the surface of said tube to be en-

gaged by said collar to force the jaws into said collar is slidable, stops at the opposite gripping position and portions at the other ends of said bore to limit the movement of end of said jaws to cause the collar to move said collar relative to said tube for the operation of said jaws. 10
5 said collar, manual means for reciprocating said tube relative to said barrel, a bushing fixed to said barrel having a bore in which

In testimony whereof I affix my signature.

CHARLES H. PATTEN.
